PAPER BOTTLE AND CONTAINER

Harold H. Pelzer, Astoria, Long Island, N. Y.

Application April 11, 1940, Serial No. 329,051

15 Claims. (Cl. 229—4.5)

This invention relates to a new and useful improvement in paper bottles and containers and, in particular, to a bottle made from heavy paper or light board stock having a body which is square in cross-section, a bottom integral therewith and raised somewhat above the bottom edge, and a neck projecting from the upper edge of the body which gradually tapers and approaches a round cross-section which it acquires at its upper end and which may be enveloped by an annular lip of a size adapted to receive any standard cap such as that used for closing glass milk bottles for example.

The essential features embodied in this invention are, first, the production of a complete bottle body from a single integral sheet of paper or light board stock, the body being hereinafter referred to as comprising a body part, a neck part, a bottom and a rim or chimb. Second, a bottle made from an integral sheet having a body part rectangular in cross-section with corners stiffened by integral vertical beads or ribs; a neck part rectangular in cross-section at the bottle shoulder and tapering into a circular formation at the mouth, the change from rectangular to circular formation being accomplished by forming V-shaped folds or pleats at the corners which when folded flat have close meeting edges on the inner side thereby providing an interior surface which after paraffining is smooth and unbroken and comparable to that of a glass bottle; and a bottom part consisting of four plies of paper so folded within the body part to form a recessed bottom and a two-ply rim or chimb. The mouth of the bottle is provided with a lip or rim preferably in the form of a double flanged metal ring attached and secured in a novel way which insures absolute security and freedom from leakage.

Since one of the important uses of this bottle is as a container for milk, the form selected for illustration in the drawing hereof and for description herein, is designed particularly for that service so that standard filling and capping equipment with which most dairies are now equipped can be used without alteration. However, it will be understood that the invention is not limited to a bottle for this purpose or to the actual or relative dimensions shown.

In the drawings—

Figure 1 is a side elevation of the bottle complete but without the cap or closure;

Figure 2 is a top plan view of the same bottle;

Figure 3 is a bottom plan view of the same bottle;

Figure 4 is a vertical cross-section of the bottle on the line 4—4 of Figure 2 viewed as indicated by the arrows;

Figure 5 is a vertical cross-section of the bottle on the line 5—5 of Figure 2 viewed as indicated by the arrows;

Figure 6 is an enlarged sectional detail of the same bottle to illustrate particularly the manner in which the lip or rim is attached and its relation to one form of closure or cap;

Figure 7 is a view similar to Figure 6 showing the same cap in its fully-seated condition;

Figures 8, 9 and 10 are top plan views illustrating the progressive steps in the making of the bottle neck pleats;

Figure 11 is a general view of the blank from which the bottle is made;

Figure 12 is a diagrammatic view, partly in cross-section, illustrating the manner in which the recessed four-ply bottom is produced;

Figures 13 and 14 are enlarged schematic views illustrating the manner in which the stiffening beads or ribs are formed on the vertical edges of the body; and

Figure 15 is a similar view illustrating a different type of vertical edge which would result from a different treatment of the blank.

As shown in Figure 11 the blank 1 from which the bottle is made consists of a flat piece of heavy paper or light board divided into four identical panels 2, 3, 4 and 5 by vertical scores 6 impressed from the side of the blank which becomes the inner side of the bottle, which is the side shown in Figure 11, so that they form outwardly-projecting ribs similar to that shown in Figure 13. Beginning at the point 7, which is the junction between the body and the neck of the bottle, panels 2, 3, 4 and 5 taper symmetrically to the top of the blank, the taper being such that when the neck is formed the edges 8 and 9 of adjacent panels will meet throughout their length. Beyond the outer edge of one of the outer panels (5, for example) is a flap 10 which, when the bottle is formed, overlaps the outer edge of the opposite panel 2 and is tightly secured thereto by a suitable adhesive.

The tapering neck portions of panels 2, 3, 4 and 5 are connected together and also the equivalent portion of flap 10 is connected to the adjacent edge of panel 5 by integral sections 11 through which scoring 6 is extended and which is also provided with additional scorings 12 and 13, impressed from the face of the blank (the underside as viewed in Figure 11) and following the edges of the panels from the point 7 at which

the neck begins to the top. Between these scorings 12 and 13 is an additional pair of scorings 14 and 15 impressed from the back of the blank (the side shown in Figure 11) which start at a point 16 slightly above point 7 and diverge symmetrically with respect to scoring 6 and scorings 12 and 13. Sections 11 project uniformly, and preferably as shown, above the upper edges of panels 2-5 so that when the bottle is formed the upper edges of the folds formed by scores 12-15 will be in alignment with the top edges of panels 2-5 and form a level seat for the neck ring.

At the line 17, which is to form the bottom edge or chimb of the bottle, panels 2-5 are crossed by a transverse scoring 18 impressed from the back or inside of the blank. Below these are four additional scorings 19-22 impressed from the face or outside of the blank which denote an edge of each of the plies of which the depressed bottom of the bottle is made. Each of these scorings is parallel to scoring 18, but scorings 20, 21 and 22 are progressively nearer to scoring 18 by the thickness of the paper or board stock from which the blank is made.

Below scorings 19-22 are four flaps 23-26, which will constitute the four-ply bottom of the bottle. Of these flap 23, which will form the inside ply, is the longest and of the same dimensions as the inside of the bottle at the bottom and lies in exact alignment with panel 2. Flap 24 is shorter by the thickness of the paper or board and the flaps 25 and 26 are progressively shorter, each by the thickness of the paper or board stock, and they lie below and in alignment with the panels 3, 4 and 5, respectively, with the exception that edges 27, 28 and 29 are offset inwardly with respect to the corresponding edges 6 of the panels by the thickness of the paper stock. The other or right-hand edge of each of flaps 24 and 25 is in line with the corresponding edge of panels 3 and 4. The other edge 30 of flap 26 is also inset with respect to the corresponding edge of panel 5 by the thickness of the stock.

From the blank the bottles may be made as follows: The blank is folded upon scorings 6 around a mandrel corresponding in size and shape to the inside of the bottle and flap 10 is folded over the outer edge of panel 2 and securely attached thereto.

This produces the box-like structure open at both ends shown in Figure 8. Since scorings 6 were impressed upon the inside of the blank the panels will fold easily and smoothly upon these lines, as will be seen from Figures 13 and 14, and there will also be produced an upstanding rib 6a (Figures 8 and 14) along each edge which will greatly stiffen the corners.

The next step is preferably to form the bottom. This is done by folding flap 23 upon scoring 19 so that it covers the lower end of the tube already formed and then pushing it bodily into the end of the tube until scoring 18 is reached, as shown in Figure 12. This depresses the inside ply 23 of the bottom into the tube to the extent of the width between scorings 18 and 19. This flap will then fit exactly the bottom end of the bottle a little above its edge, as best shown in Figure 12, the connecting portion 31 between it and panel 2 lying snugly against the panel.

The presence of portion 31 reduces one dimension of the space immediately below flap 23 by the thickness of the paper stock, but this has been provided for in the dimensions and positioning of flap 24, which can now be similarly bent on scor-

ing 20 and similarly pushed bodily into the end of the tube until it rests against flap 23 when it will fill the entire space. The third flap 25 is treated in a similar manner and followed by the

fourth flap 26. Each flap is secured to contiguous flaps by a suitable adhesive with the result that a solid four-ply liquid-tight bottom is formed slightly above the two-ply bottom edge or chimb of the bottle formed by webs 31, as indicated in Figures 4 and 5, which edge coincides with scoring 18 and, consequently, lies in the same plane throughout.

The next step is to form the neck of the bottle. This is done by bending panels 2, 3, 4 and 5 inwardly until edges 8 and 9 of corresponding panels meet each other. In doing this the fan-shaped pleating sections 11 will assume a pyramidal shape upon scorings 12, 13, 14, 15 and 6 in the manner shown in Figure 9, after which the pleats are flattened by pressure into the rib shown in Figure 10.

It will be noted from Figures 5, 9 and 10 that the inside of the neck of the bottle consists entirely of the panels 2, 3, 4 and 5, and that the edges 8-9 of these panels meet throughout the length of the neck and are overlaid by the integral flattened pleats. Thus the surface of the inside of the neck is substantially smooth and unbroken and the junction lines between adjacent panels will be automatically sealed when the bottle is coated with paraffin or subjected to any other similar coating process. In any event the pleats are completely flattened, there are no incidental depressions or cavities into which the contents of the bottle can pass, and since they are integral with the panels there is no possibility of leakage. Also since the pleating sections 11 extend slightly above the top of the blank, as shown in Figure 11, their edges will align with the top edges of the panels when the neck is completed, as shown in Figures 5 and 10. It will also be noted that by this method of formation the shape of the neck has been converted from a square at its lower end to a circle at its upper edge.

The upper edge of the neck may be permanently retained by any desired sort of rim, but the rim 32 illustrated in Figures 6 and 7 has been found highly satisfactory both with regard to the neck and its adaptability for receiving the combined cap and hood illustrated. This rim consists of a circular metal channel, the outer flange 33 of which is longer than the inner flange 34. This is pressed over the edge of the neck of the bottle, including the pleats, and the edges of both flanges are curved towards each other as shown in Figures 6 and 7. Since the outer edge 35 of the rim is below the inner edge 36 the bottle neck is offset outwardly as shown, and is securely clinched between the edges and sides of the rim. The connection thus made is not only mechanically secure, but liquid tight.

The form of closure shown is a combined cap and hood, which consists of a cap portion 37 of a diameter slightly larger than the internal diameter of rim 32, so that when inserted it will fit securely under the shoulder formed by the curved inner edge 36 of the rim. From this cap portion 37 the hood portion 38 extends upwardly and then curves downwardly to form an apron 39, as shown in Figure 6, to envelope the rim. If desired, the lower edge 40 of apron 39 portion may then be bent inwardly under pressure and heat so that it rests snugly against the neck of the bottle just below the outer edge of the rim

as shown in Figure 7, where it may be retained by paraffin or an adhesive. The advantage of a combined cap and hood of this type is that the lip of the bottle is fully protected from contamination and also any dirt which may lie upon the cap portion 37 cannot reach the contents of the bottle when the cap is removed as will almost inevitably happen where a simple disk-like cap is used.

The four-ply construction of the bottom of this bottle not only eliminates all possibility of sagging, but also greatly stiffens the entire body. The body of the bottle is further stiffened by the ribs 6a extending longitudinally along each edge, and the neck of the bottle is stiffened by reason of the pleats being erected from the four corners and also by the metal rim, with the result that an extremely sturdy and rigid bottle is produced capable of holding any ordinary liquid without material bulging, or other distortion. Furthermore, this bottle being square in cross-section has the great advantage of occupying much less space than a round bottle of equivalent height and capacity and is also very inexpensive to manufacture because of the materials employed and the simple manufacturing operations required. Since a bottle of this sort is usually coated with paraffin or other coating, the edges of the neck panels will be sealed as already described, and also the edges of the inside ply of the bottom so that its inherent liquid tightness is supplemented and the interior isolated from the other parts as completely as in a glass bottle.

The stippled surfaces shown in Figures 11 and 12 represent those to which adhesive may be applied most advantageously, but it will be understood that this may be varied if desired. The adhesive may be a wet adhesive applied before the blank is folded or may be a plastic the adhesive properties of which are realized by the subsequent application of heat and pressure. Paraffin and many other coating materials are included in the term "adhesive" as used herein since they possess adhesive properties which frequently are adequate.

I claim:

1. A blank for a paper bottle or container which includes a body portion consisting of four identical rectangular panels, a straight scoring between adjacent panels, a bottom portion below each panel, a continuous strip connecting said bottom portions to the corresponding panels, the portion of the strip below an outside panel being the widest and each of the succeeding portions below the remaining panels being narrower than the preceding one by the thickness of the blank, the width of an outside bottom portion being equal to the width of the corresponding panel, the width of the two intermediate bottom portions being less than the width of said outside bottom portion by the thickness of the blank, the width of said remaining bottom portion being less than the width of said outside bottom portion by twice the thickness of the blank, the length of said outside bottom portion being equal to the width of the corresponding panel, the length of the next bottom portion being less than the width of said outside bottom portion by the thickness of the blank, and the length of said other two bottom portions being less than the length of said outside bottom portions by twice the thickness of the blank.

2. A blank for a paper bottle which includes a body portion consisting of four rectangular

panels spaced by longitudinal scorings, four bottom portions one below each panel, an intermediate strip connecting said bottom portions to said panels, the top and bottom edges of said bottom portions being progressively stepped towards the body portion by the thickness of the blank, the side edges of an end bottom portion being in alignment with the side edges of the corresponding panel, one side edge of the three succeeding bottom portions being offset inward with respect to the corresponding edge of the corresponding panel by the thickness of the blank, the other edge of the two intermediate bottom portions being in alignment with the corresponding edge of the corresponding panel and the remaining side edge of the remaining bottom portion being stepped inward in relation to the corresponding edge of the corresponding panel by the thickness of the blank.

3. A blank for a paper bottle which includes a body portion consisting of four rectangular panels spaced by longitudinal scorings, four bottom portions one below each panel, an intermediate strip connecting said bottom portions to said panels, the top and bottom edges of said bottom portions being progressively stepped towards the body portion by the thickness of the blank, the side edges of an end bottom portion being in alignment with the side edges of the corresponding panel, one side edge of the three succeeding bottom portions being offset inward with respect to the corresponding edge of the corresponding panel by the thickness of the blank, the other edge of the two intermediate bottom portions being in alignment with the corresponding edge of the corresponding panel and the remaining side edge of the remaining bottom portions being stepped inward in relation to the corresponding edge of the corresponding panel by the thickness of the blank, and a neck portion consisting of four upwardly tapering panels, each forming a continuation of a body panel, and each connected to an adjacent neck panel.

4. A blank for a paper bottle which includes a body portion consisting of four rectangular panels spaced by longitudinal scorings, four bottom portions one below each panel, an intermediate strip connecting said bottom portions to said panels, the top and bottom edges of said bottom portions being progressively stepped towards the body portion by the thickness of the blank, the side edges of an end bottom portion being in alignment with the side edges of the corresponding panel, one side edge of the three succeeding bottom portions being offset inward with respect to the corresponding edge of the corresponding panel by the thickness of the blank, the other edge of the two intermediate bottom portions being in alignment with the corresponding edge of the corresponding panel and the remaining side edge of the remaining bottom portion being stepped inward in relation to the corresponding edge of the corresponding panel by the thickness of the blank, and a neck portion consisting of four upwardly tapering panels, each forming a continuation of a body panel, and each connected to an adjacent neck panel by a fan-shaped pleating section.

5. A blank for a paper bottle having a rectangular body and conical neck, which comprises a body section, a neck section, and bottom sections, the body section being connected to the bottom sections by an integral intervening relatively narrow strip which becomes progressively

narrower in step-like form from one side of the blank to the other, and the bottom consisting of a plurality of divided and progressively shorter sections projecting from the intervening narrow stepped strip.

6. A blank for a paper bottle having a rectangular body and conical neck, which comprises a body section, a neck section, and bottom sections, the body section consisting of four integral panels spaced by score lines, the bottom consisting of four flaps, one adjacent the lower end of each body panel, each bottom flap being progressively shorter, and connected to the panels by an intervening relatively narrow integral strip section having parallel top and bottom score lines, the width of said strip being progressively narrower in steps each equal in length to the width of the adjacent body panels, and the width of the steps decreasing successively equal to the thickness of the blank.

7. A blank for a paper bottle having a rectangular body and conical neck, which comprises a body section, a neck section, and bottom sections, the body section consisting of four integral panels spaced by score lines, the bottom consisting of four flaps, one adjacent the lower end of each body panel, each bottom flap being progressively shorter, and connected to the panels by an intervening relatively narrow integral strip section progressively narrower in steps equal in length to the width of the adjacent body panels and spaced by score lines, the upper score being a straight line and the lower score of each successive step being parallel to the upper score line and spaced progressively nearer thereto by the thickness of the blank.

8. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, and a multi-ply bottom.

9. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, said folds being so proportioned relative to the mouth diameter that the adjacent edges of the interior neck surface formed by the folds are drawn into close proximity from the body shoulder to the mouth, and a multi-ply bottom.

10. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, vertically extending beads at the body angles, and a multi-ply bottom.

11. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, a bottom chimb, and recessed multi-ply bottom.
12. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, a two-ply bottom chimb, and recessed four-ply bottom.
13. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, vertically extending beads at the body angles, a two-ply bottom chimb, and recessed four-ply bottom.
14. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, a two-ply bottom chimb formed by a stepped strip section between the body and bottom parts, and a recessed four-ply bottom formed by progressively shorter bottom flaps projecting successively from the stepped sections of said strip.
15. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, said folds being so proportioned relative to the mouth diameter that the adjacent edges of the interior neck surface formed by the folds are drawn into close proximity from the body shoulder to the mouth, vertically extending beads at the body angles, a two-ply bottom chimb formed by a stepped strip section between the body and bottom parts, and a recessed four-ply bottom formed by progressively shorter bottom flaps projecting successively from the stepped sections of said strip.
16. A bottle having a body angular in cross-section, a tapering neck, and reinforced bottom, composed entirely of a single integral sheet of paper with a single continuous joint or seam at the body and neck, and comprising when formed an angular body, a truncated pyramidal-conic neck extending from bottle shoulder to mouth, V-shaped neck reinforcing folds projecting from the angles of the body at the shoulder to the mouth, said folds being so proportioned relative to the mouth diameter that the adjacent edges of the interior neck surface formed by the folds are drawn into close proximity from the body shoulder to the mouth, vertically extending beads at the body angles, a two-ply bottom chimb formed by a stepped strip section between the body and bottom parts, and a recessed four-ply bottom formed by progressively shorter bottom flaps projecting successively from the stepped sections of said strip.

HAROLD H. PELZER.
